(57) **CLAIM**

The ornamental design for a tilt monitor and brackets for a digital camera as shown and described.

DESCRIPTION

FIG. 1 is a rear, top and right side perspective view of a first embodiment of a tilt monitor and brackets for a digital camera showing our new design;

FIG. 2 is a rear, top and left side perspective view thereof; FIG. 3 is a rear, bottom and left side perspective view thereof;

FIG. 4 is a rear, bottom and right side perspective view thereof;

FIG. 5 is a rear view thereof;

FIG. 6 is a top plan view thereof;

FIG. 7 is a bottom plan view thereof;

FIG. 8 is a right side view thereof;

FIG. 9 is a left side view thereof;

FIG. 10 is a cross-sectional view thereof, taken along line 10-10 in FIG. 6;

FIG. 11 is a cross-sectional view thereof, taken along line 11-11 in FIG. 8;

FIG. 12 is a cross-sectional view thereof, taken along line 12-12 in FIG. 8;

FIG. 13 is a cross-sectional view thereof, taken along line 13-13 in FIG. 8;

FIG. 14 is a cross-sectional view thereof, taken along line 14-14 in FIG. 8;

FIG. 15 is a rear, bottom and right side perspective view of the tilt monitor, shown with the camera body omitted for ease of illustration;

FIG. 16 is a rear, bottom and left side perspective view of the tilt monitor, shown with the camera body omitted for ease of illustration;

FIG. 17 is a rear, top and right side perspective view of the tilt monitor and brackets for a digital camera, shown in a first alternate configuration; FIG. 18 is a rear, top and right side

(Continued)

perspective view thereof, shown with the tilt monitor and brackets for a digital camera in a second alternate configuration;

FIG. 19 is a rear, top and right side perspective view of a second embodiment of a tilt monitor and brackets for a digital camera showing our new design;

FIG. 20 is a rear, top and left side perspective view thereof; FIG. 21 is a rear, bottom and left side perspective view thereof;

FIG. 22 is a rear, bottom and right side perspective view thereof;

FIG. 23 is a rear view thereof;

FIG. 24 is a top plan view thereof;

FIG. 25 is a bottom plan view thereof;

FIG. 26 is a right side view thereof;

FIG. 27 is a left side view thereof;

FIG. 28 is a cross-sectional view thereof, taken along line 28-28 in FIG. 24;

FIG. 29 is a cross-sectional view thereof, taken along line 29-29 in FIG. 26;

FIG. 30 is a cross-sectional view thereof, taken along line 30-30 in FIG. 26;

FIG. 31 is a cross-sectional view thereof, taken along line 31-31 in FIG. 26;

FIG. 32 is a cross-sectional view thereof, taken along line 32-32 in FIG. 26;

FIG. 33 is a rear, bottom and right side perspective view of the tilt monitor, shown with the camera body omitted for ease of illustration;

FIG. 34 is a rear, bottom and left side perspective view of the tilt monitor, shown with the camera body omitted for ease of illustration;

FIG. 35 is a rear, top and right side perspective view of the tilt monitor and brackets for a digital camera, shown in a first alternate configuration; and,

FIG. 36 is a rear, top and right side perspective view thereof, shown with the tilt monitor and brackets for a digital camera in a second alternate configuration.

The broken lines depict portions of the tilt monitor and brackets for a digital camera that form no part of the claimed

design. Additionally, the dash-dot lines denote the boundary of the claim and form no part of the claimed design.
